UNITED STATES PATENT OFFICE.

EVERETT G. COUCH, OF WASHINGTON, DISTRICT OF COLUMBIA.

PORCH-SWING.

1,371,197.

Specification of Letters Patent.

Patented Mar. 8, 1921.

Application filed November 6, 1919. Serial No. 336,136.

To all whom it may concern:

Be it known that I, EVERETT G. COUCH, a citizen of the United States, residing at Washington, District of Columbia, have invented certain new and useful Improvements in Porch-Swings; and I do hereby declare the following to be a full, clear, and exact description of the invention, such as will enable others skilled in the art to which it appertains to make and use the same.

This invention relates to swings, and while particularly adapted to porch and lawn swings, is not limited thereto.

An object of this invention is to provide a comfortable, attractive and easily operated swing and one with a durable, attractive and comfortable cover that is weatherproof and can be easily knocked down.

A further object of this invention is to reduce the manual power in operating a swing of this character and also to reduce the cramping of the legs in so operating a swing of this character, and to provide a natural easy movement to the legs in operating such a swing.

A further object of this invention is to provide an improved means of suspending a swing of this character and especially to provide a quickly installed suspension means, and also one that will resist lateral motion and at the same time operate with minimum friction.

A further object of this invention is to provide an improved seat structure and means of supporting said structure and to provide a maximum carrying capacity with a minimum weight.

With these and other objects in view the invention consists in the construction, the combination, the details and arrangement of parts as hereinafter more fully described and claimed.

In the drawings:

Figure 1 is a perspective of the swing in skeleton with the suspension means broken away.

Fig. 2 is substantially the same as Fig. 1 with the skeleton part covered for use.

Fig. 3 is a diagrammatic view illustrating the position of the different movable parts of said swing and suspension in different positions of its swing.

Fig. 4 is an enlarged fragmentary detail

showing the mount at the ceiling of the main suspension member.

Fig. 5 is an enlarged fragmentary detail of the means of joining the main suspension mount to the body of the swing.

Fig. 6 is a fragmentary end elevation of Fig. 4.

Fig. 7 is an enlarged bottom view of one of the ceiling brackets.

Fig. 8 is a modified form with upholstered seat and back.

In detail the invention consists of a yoke 65 bar 2 preferably of strap iron to which is riveted a pair of angle irons 3 and 3', angle irons 3 and 3' being joined together by angle irons 4 and 4' so that angle irons 3 and 3' and 4 and 4' form a rectangular seat 70 and are braced to yoke 2 by braces 5 and 5'. A rod 6 joins the ends of yoke 2 at 7 and has pivoted thereon at 8 a pair of straps 9 and 9' joined by a rod 10, said straps 9 and 9' carrying a pedal board 11 suitably affixed 75 thereto and preferably by bolts 12. Affixed to the sides of yoke 2 are brackets 13 carrying eyes for receiving in screw thread relation rods 14. Similar brackets 15 are af- 80 fixed suitably to angle irons 3 and 3' for carrying rods 16 similar to rods 14. Rods 14 and 16 are provided with hooks to hook into rings 17 and 17'. Also hooking into rings 17 and 17' are respectively hooks 18 and 18' suspended from respective chains 85 19 and 19'. Chains 19 and 19' are suspended from rods 20 and 20', said rods 20 and 20' being provided respectively with hooks 21 and 21' and eyes 22 and 22'. Eyes 22 and 22' are made of sufficient size to admit 90 the insertion of brackets 23 and 23' there- through, and brackets 23 and 23' are re- spectively affixed to the ceiling or other suit- able suspension mount by screws 24. Rods 20 and 20' are held in desired alinement by 95 a pipe section 25 drilled at 26 and 26' for re- ceiving respectively rods 20 and 20'. Aux- iliary chains 19^a and 19^b are provided with hooks 18^a and 18^b to be inserted respectively in eyes 17^a and 17^b. Chains 19^a and 19^b are 100 mounted relative to the ceiling in substan- tially the same manner as chains 19 and 19'.

An auxiliary chair 26 provided with in- 105 verted V shaped extensions 27 and 27' and with slots 28 and 28' is slipped over the main chair before the insertion of rods 14

and 16. Auxiliary covers are also provided for chains 19 and 19', 19^a and 19^b. These auxiliary covers are numbered 29 in the drawings.

5 In mounting this swing to a porch, brackets 23 are first inserted through eyes 22 and 22' in rods 20 and 20' and also like brackets are inserted in similar rods from chains 19^a and 19^b and the said brackets are then 10 affixed to the ceiling or other suitable mounts in proper relation to allow a free pivoting of the said rods. These rods, together with the cross pipe 25, form a permanent fixture. At suitable times, when desired to utilize 15 the swing, chains 19, 19' and 19^a and 19^b are respectively hooked in their receiving hooks 21 and 21' and like hooks in the mount for chains 19^a and 19^b.

In assembling the swing proper, which is 20 preferably shipped with rods 14 and 16 removed, auxiliary seat 26 is inserted from the top over the skeleton portion and then rods 14 and 16 are screwed into the eyes in respective brackets 13 and 15 and the wicker 25 covering inserted over the chains 19 and 19' and 19^a and 19^b, and the hooks 18 and 18' and 18^a and 18^b respectively inserted into rings 17 and 17' and eyes 17^a and 17^b, when 30 the swing is ready for suspension to the ceiling mount as hereinbefore described.

In the arc of movement illustrated in the diagrammatic view in Fig. 3 it will be observed that by having the pivotal point of the pedal member to the back of the seat 35 and in the position illustrated that upward and downward movement of the pedal throughout the usual arc of swinging very slightly varies the angularity of the pedal relative to the normal position of the leg of 40 the operator so that there is but slight movement of the ankle necessary in propelling the swing. It will further be observed at the positioning here shown by the extension of the radius from its pivot to the pedal and 45 the other elements herein that the arc of the pedal upon this pivot varies relatively but slightly from a right angle to the seat, thus maintaining substantially a normal position of the legs of the operator relative to the 50 seat.

It will further be observed that the arrangement herein illustrated will require a relatively short stroke of the foot in propelling this swing.

55 Eyes 22 and 22' have much greater diameter than the diameter of the pivotal bearing therefor on brackets 23. It is obvious that with this greater relative diameter that a point suspension is obtained and that friction is very materially reduced.

In the modified form shown in Fig. 8, I prefer to dispense with the yoke 2 and I provide the chair with an upholstered back 60 and upholstered seat 31.

65 In both forms of construction herein indi-

cated the wicker-work seat is securely fastened to the metal frame work as shown in the drawings of the modified form.

Claims:

1. In a swing, a seat including a bar bent 70 in U shape and forming a back and rear legs to said seat, a bar joining said U bar, a pedal, said pedal pivotally mounted upon said joining bar, a seat bottom extending in front of said U bar, and means for suspending said pedal and said seat.

2. In a swing, a seat provided with suspension mounts comprising a U bar bent to form the rear legs and back of said seat, 80 angle irons forming the bottom of said seat, and a brace for said U bar also forming a mount for said suspension means.

3. In a swing, a seat provided with suspension mounts comprising a U bar bent to form the rear legs and back of said seat, 85 angle irons forming the bottom of said seat, a brace for said U bar also forming a mount for said suspension means, and a pedal pivotally mounted to said legs and provided with independent suspension means. 90

4. In a swing, a skeleton seat, means for suspending said skeleton seat, and a wicker body provided with openings underneath to slip over said skeleton seat.

5. In a swing, a skeleton seat, means for suspending said skeleton seat, and a wicker body provided with openings underneath to slip over said skeleton seat, said skeleton seat provided with detachable suspension supports mounted at the front and rear of 100 said seat and engaging a suspension member substantially medial of said seat, and said wicker body provided with channels for receiving said supports after the seat body has been inserted over said skeleton. 105

6. In a swing, a skeleton seat, means for suspending said skeleton seat, a wicker body provided with openings underneath to slip over said skeleton seat, and said suspension means including a suspension member and a wicker casing for said suspension member, said wicker casing for said suspension member joining with said wicker body when said swing is set up for use. 110

7. In a swing, a skeleton seat, means for suspending said skeleton seat, a wicker body provided with openings underneath to slip over said skeleton seat, and a pedal provided with suspension means, said pedal pivotally mounted to said skeleton seat and extending in front of said body, and said body recessed to admit of movement of said pedal on said pivotal mount. 115

8. In a swing, a skeleton seat, means for suspending said skeleton seat, and a wicker body provided with openings underneath to slip over said skeleton seat, said body provided with mounts for auxiliary cushions. 120

In testimony whereof I affix my signature. 125
EVERETT G. COUCH
